[57] CLAIM

The ornamental design for a combination digital clock and lamp base, as shown and described.

DESCRIPTION

FIG. 1 is a top front perspective view of a combination

digital clock and lamp base;

FIG. 2 is a front elevational view thereof;

FIG. 3 is a rear elevational view thereof;

FIG. 4 is a right side elevational view thereof;

FIG. 5 is a left side elevational view thereof;

FIG. 6 is top front perspective view of a second embodiment of my new design of FIGS. 1-5, FIGS. 2-5 being the corresponding views of this embodiment;

FIG. 7 is a top and front perspective view of a third embodiment of my new design of FIGS. 1-5, FIGS. 2-5 (with a double row of buttons) being the corresponding views of this embodiment;

FIG. 8 is a top and front perspective of a fourth embodiment of my new design of FIGS. 1-5 with the compartment lid shown in an open position, it being understood that the top thereof is flat and plain with FIGS. 2-5 being the corresponding views of this embodiment;

FIG. 9 is a bottom plan view of the four embodiments of my design shown in FIGS. 1-8;

FIG. 10 is a top and front perspective view of a fifth embodiment of my new design (with a double row of buttons), the front halves of the right and left sides thereof being visible in this view;

FIG. 11 is a top and rear perspective view of the fifth embodiment of FIG. 10, the rear halves of the right and left sides thereof being visible in this view; and,

FIG. 12 is a bottom plan view of the embodiment of the design of FIGS. 10 and 11.
